Att. Inventor
Addison C. Fletcher

United States Patent Office.

ADDISON C. FLETCHER, OF NEW YORK. N. Y.

Letters Patent No. 73,791, dated January 28, 1868; antedated January 16, 1868.

IMPROVEMENT IN BALE-FASTENERS.

The Schedule referred to in these Letters Patent and making part of the same.

TO ALL WHOM IT MAY CONCERN:

Be it known that I, ADDISON C. FLETCHER, of the city, county, and State of New York, have invented a certain new and useful Improvement on Bale-Fasteners, applicable also to securing other packages, of which the following is a full, clear, and exact description, reference being had to the accompanying drawing, forming part of this specification, and in which—

Figure 1 represents a plan, face, or flat view of a bale-fastener, constructed according to my improvement, and with a baling-hoop on its end sections applied thereto.

Figure 2, a longitudinal section of the same.

Figure 3, a plan or face view of the plate of which the fastener is composed detached, and

Figure 4, a longitudinal section of portion of the fastener-plate, slightly modified in its construction to adapt it to holding one end of the baling-hoop without the aid of a separate cross-locking pin.

Like letters indicate like parts in both figures.

The nature of my invention consists in a peculiarly-constructed slotted plate, through which one or both ends of the baling-hoop or wire are slipped a second time, or doubled and bridged formation to the plate, over one or more of certain of the slots, through which a pin or nail is passed to bind or lock the doubled ends of the hoop or wire between the end or ends of the plate and slot, over the edge or edges of which the hoop or wire is doubled.

Referring to the accompanying drawing, A is a metallic plate constructed with a slot or opening, *a*, in it, preferably of a width corresponding to the width, or thereabouts, of the baling-hoop or wire, hoop-iron being preferred for baling cotton, and wire, it may be, for baling hay, the shape or material of which the baling-tie is formed, varying with the description of the goods to be baled, and other circumstances. It will suffice here, however, to refer to the tie as made of hoop-iron. B is the one end of the tie, and C the other. The one of these ends may be secured, in any suitable manner, to the plate A, between its end and the opening *a*; thus it may be slipped through a second time, that is, doubled or twisted back or over the one edge of the opening *a*, and be locked as hereinafter described, or as represented in fig. 4; its doubled end passed underneath the plate through a second slot, *b*, that may or may not be bridged or arched, as hereinafter referred to. Supposing, however, both ends of the baling-hoop to be locked, then, in addition to two cross-slots or openings *b* in the plate, between the opening *a* and ends of the plate, I form bridges or arches *c*, on the outer surface thereof, on the opposite sides or edges of the doubled portions of the baling-hoop, so that by simply passing a nail or pin, or nails or pins, D, through the bridges or arches *c*, as represented in figs. 1 and 2, the doubled ends of the baling-hoop are sprung at their crossing over the slots *b*, and securely held or locked, the springing of the hoop-iron or wire serving to bear the nails or pins against the bridges *c*, and hold them in place, but so that they may be removed on tapping them with the hammer, when it is desired to unbale.

A bale-fastener thus constructed is as simple as it is efficient. The device, it is obvious, may be applied as a fastener to packages of various descriptions other than bales.

What I claim as my invention, and desire to secure by Letters Patent, is—

A bale-fastener composed of a plate, A, provided with an opening, *a*, and a slot or slots, *b*, one or both of the latter having arches *c* at their sides, for use in connection with a pin or nail, or pins or nails, D, to secure the bent or doubled end or ends of the baling-hoops or wires, substantially as specified.
